UNITED STATES PATENT OFFICE.

HOWES C. WALLACE, OF SALT LAKE CITY, UTAH.

STREET AND STATION INDICATOR.

No. 832,643.

Specification of Letters Patent.

Patented Oct. 9, 1906.

Application filed November 18, 1904. Serial No. 233,308.

To all whom it may concern:

Be it known that I, HOWES C. WALLACE, a citizen of the United States, and a resident of Salt Lake City, in the county of Salt Lake and State of Utah, have invented a new and Improved Street and Station Indicator, of which the following is a full, clear, and exact description.

My invention relates to devices for indicating the names of stations or streets in railway-cars, street-cars, and like vehicles; and the purpose of the invention is to provide a device of the character described by means of which an advertisement may be made to appear simultaneously with the display of the name of a station or a street.

Another purpose of the invention is to provide a very simple device capable of producing the above-mentioned results and one which will be reliable in action and under the perfect control of the operator and whereby the device will effectually operate to display the names of the proper streets and stations whether the vehicle be traveling toward one or toward the other terminal of the route.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a front elevation, partly in section, of the device applied to the clearstory of a car, which latter appears in section. Fig. 2 is a vertical transverse section taken about centrally through the indicator, and Fig. 3 is a perspective view of the web, showing the arrangement of the station-names thereon.

A represents the clearstory of a car, B the body thereof, and B' a door at the end of the car or a window at such point, above which the indicator is secured within the said clearstory A, as is illustrated in Fig. 1. The indicator consists of a casing D of any suitable form. Preferably, however, the casing is made rectangular, as illustrated. The said casing at the front is provided with three sight-openings—namely, an upper opening 10, an intermediate one 11, and a lower one 12—the said sight-openings being one above the other and in parallelism, as is shown best in Fig. 1.

55 A roll-shutter 13 is provided for the upper sight-opening 10, which roll-shutter when

not in use, as is shown in Fig. 2, is located between a guide 14 and the top of the casing D. A second roll-shutter 16 is provided for the lower sight-opening 12, and when this shutter is not in use it is located between a guide 18 and the bottom of the casing D. In the drawings the lower shutter 16 is shown closed, as in the operation of the device if one shutter is opened the other is closed. These 60 shutters are usually operated by hand through the medium of a knob or handle 15, attached to their outer end portions and extending out through the opening.

The sight-opening 10 is provided with a 70 transparent pane 10^a, over which the shutter 13 passes when said shutter is closed, and the intermediate sight-opening 11 is provided with a transparent panel 11^a, which is always uncovered. The sight-opening 12 is provided 75 with a transparent panel 12^a, which is covered by the shutter 16 when the said shutter is closed, as is shown in the drawings.

A drum 19 is journaled in the casing D at the rear of the upper sight-opening 10, and a 80 second drum 22 is mounted to revolve in the said casing at its lower portion and at the rear of the lower sight-opening 12. The trunnions of the upper drum 19 extend through the casing at its ends, and one trunnion is 85 provided usually with a bevel-gear 20 and the other trunnion with a sprocket-wheel 21, as is shown in Fig. 1.

With reference to the lower drum 22, but one of its trunnions 23 extends out beyond 90 the end of the casing D, and this trunnion is provided with a sprocket-wheel 24, located beneath the sprocket-wheel 21 of the upper drum. A crossed belt 25 is passed over the two sprocket-wheels, as is illustrated also in 95 Fig. 1.

A curtain C is employed in connection with the two drums 19 and 22, the ends of the said curtain being secured to the said drums, as is illustrated in Fig. 2. This curtain is of greater width than the length of the 100 sight-openings, and the said curtain when passing from the upper drum 19 is carried over a guide-pulley 26 above and to the rear of the drum and then over a corresponding front guide-pulley 27 and from thence downward in front of the upper sight-opening 10 and the intermediate sight-opening 11. At the bottom of the intermediate sight-opening 11 the curtain is carried under and in engagement with a front guide-roller 28 and thence 105 horizontally rearward over a second guide-roller 29, forming a stretch of the curtain 110.

above the said lower drum, and then the said curtain is carried vertically downward from the guide-roller 29, which may be termed an "intermediate" guide-roller, down to and over a guide-roller 30 at the rear of and below the lower drum 22. The curtain is then carried forward, making a horizontal stretch, and upward over a forward lower guide-roller 31, and thence upward to and over a guide-roller 32, located below the intermediate front guide-roller 28, above referred to, and from this guide-roller 32 the curtain is carried and secured to the said lower drum 22, thus providing a vertical forward stretch of the curtain at the rear of the lower sight-opening 12, as the guide-roller 31 is adjacent to the lower edge of the said sight-opening 12 and the roller 32 is adjacent to the upper edge of the same opening.

20 The names of the stations are produced upon both faces of the curtain; but the name of the last point on the route is on one side of the curtain opposite the first name on the route which is at the other side of the curtain and upon what may be termed practically the "front face" of the curtain, advertisements of any description are produced immediately following the names of the stations, as no matter whether the curtain is moving 25 from the drum 19 to the drum 22 or the reverse the advertisements are to be displayed 30 at the intermediate sight-opening 11, while the names of the stations when the vehicle is traveling in one direction are read at the upper sight-opening 10, and when the car is traveling in the opposite direction, or toward the other end of the route, the names of the stations are read at the lower sight-opening 12, and by reason of the arrangement of the 35 guide-pulleys 29, 30, 31, and 32 the reverse side of the curtain is presented to the lower sight-opening 12, while the opposite or front face of the curtain is presented to the intermediate sight-opening and the upper sight-opening, as is shown in Fig. 2. Consequently when the car is traveling toward one 40 end of the route the shutter of the lower sight-opening 12 is closed and the shutter of the upper sight-opening 10 is opened, and 45 when the car is traveling toward the opposite end of the route the reverse arrangement of the shutters is made.

50 The curtain or apron C is operated usually through the medium of a shaft 33, journaled in a hub 34 in the drum 22, and an

the shutters is made.

55 The curtain or apron C is operated usually through the medium of a shaft 33, journaled in suitable bearings in the clearstory, and one end of the shaft is so located as to be within convenient reach of the conductor or other operator. At this end of the shaft a crank-arm 35 is shown attached to facilitate the 60 turning of the shaft in either one or the other direction to turn the drums 19 and 22 in corresponding directions, and this action is obtained usually by securing a bevel-gear 34 on the shaft 33 and causing it to mesh with the 65 gear 20, carried by the upper drum 19. In

order that attention shall be drawn to the change of display at the sight-openings in the casing, a bell 36 is mounted on the casing, and this bell has a different tone from that usually employed in the working of a street-car. This bell is shown operated through the medium of a connected crank-arm 37, to which one end of a bell-cord 38 is secured, said bell-cord 38 being led to any convenient point in the car over suitable guide-pulleys 39. 75

The indicator shown in the drawings is intended to be used in a car where the seats face in the direction the car is traveling, and in such case it is obvious that there must be an indicator at each end of the car, because when the return trip is made the seats are turned over and face the other end of the car. One indicator is used in the down trip, for example, and the other upon the return trip, the first sign or name shown on the return trip being that of the last street or stop on the down trip. For instance, if the car is traveling on Washington avenue and One Hundredth street is the last stop, at which point the seats are turned and the return trip is commenced, the indicator in view will show "100th st." The next street will be "90th st." the next "89th st." and so on. When the starting-point is reached, the last street shown will be "1st st." for example. When the car starts upon its second trip and the seats are again turned, the indicator then faced and which was formerly operated will show "1st st." since the last street shown on that indicator was "100th st." and the shutter at that opening was closed and the shutter at the other opening was opened, opposite which latter opening the name "1st st." was left by the movement of the curtain. Thus it will be observed that the upper and lower openings will show "1st st." every alternate trip and that duplicate names on both sides of the curtains are necessary.

Having thus described my invention, I claim as new and desire to secure by Letters Patent—

1. In a station-indicator, a casing having two sight-openings for the display of the names of stations, and an interposed sight-opening for the simultaneous display of an advertisement, independent shutters for closing either opening for displaying the names of stations, a curtain crossing all of the sight-openings, having names and advertising matter produced consecutively thereon, the name of one terminal of the route on the curtain being opposite the name of the other terminal of the route on the other side of the curtain, and guide and actuating devices for the curtain. 115
120
125

2. In a station-indicator, a casing having alining sight-openings therein, including an upper, a lower and an intermediate opening, roll-shutters for the upper and lower sight-openings, drums journaled in the casing, one 130

back of the upper sight-opening and the other back of the lower sight-opening, a curtain having its ends attached to the drums and provided with display matter on both 5 faces, which matter reads in opposite directions on the opposite faces, guide-rollers for the curtain, arranged to direct the curtain to the sight-openings in two display-stretches, one stretch facing two sight-openings and the 10 other stretch a single sight-opening and a

mechanism for moving both drums simultaneously in one or the other direction.

In testimony whereof I have signed my name to this specification in the presence of two subscribing witnesses.

HOWES C. WALLACE.
